US00D992989S

(12) **United States Design Patent** (10) **Patent No.:** **US D992,989 S**
(45) **Date of Patent:** **** Jul. 25, 2023**

(54) **TRIMMER LINE BLADE**(71) Applicant: **Aero-Flex Technologies, Inc.**, Rock Hill, SC (US)(72) Inventor: **Vincent D. Morabit**, Rock Hill, SC (US)(73) Assignee: **AERO-FLEX TECHNOLOGIES, INC.**, Rock Hill, SC (US)(***) Term: **15 Years**(21) Appl. No.: **29/826,386**(22) Filed: **Feb. 11, 2022**(51) **LOC (14) Cl.** ..... **08-03**(52) **U.S. Cl.**USPC ..... **D8/8**(58) **Field of Classification Search**

Primary Examiner — Sheryl Lane*Assistant Examiner* — Leisha N Price(74) *Attorney, Agent, or Firm* — Nixon & Vanderhye P.C.(57) **CLAIM**

The ornamental design for a trimmer line blade, as shown and described.

DESCRIPTION

FIG. 1 is a perspective view of a trimmer line blade according to an exemplary embodiment;

FIG. 2 is a top view thereof;

FIG. 3 is a bottom view thereof;

FIG. 4 is a front view thereof;

FIG. 5 is a back view thereof;

FIG. 6 is a left side view thereof;

FIG. 7 is a right side view thereof; and,

FIG. 8 is an alternative perspective view thereof.
